(No Model.)

C. E. CARPENTER.
ELECTRIC HEATING APPARATUS.

No. 415,856.

Patented Nov. 26, 1889.

UNITED STATES PATENT OFFICE.

CHARLES E. CARPENTER, OF MINNEAPOLIS, MINNESOTA, ASSIGNOR OF FOUR-SIXTHS TO F. W. NEVENS AND JNO. W. KELLY, BOTH OF SAME PLACE.

ELECTRIC HEATING APPARATUS.

SPECIFICATION forming part of Letters Patent No. 415,856, dated November 26, 1889.

Application filed August 6, 1889. Serial No. 319,960. (No model.)

To all whom it may concern:

Be it known that I, CHARLES E. CARPENTER, a citizen of the United States, residing in the city of Minneapolis, in the county of Hennepin and State of Minnesota, have invented certain new and useful Improvements in Electro-Heating Apparatus, of which the following is a specification.

This invention relates to improvements in electro-heating apparatus in which heretofore a carbon resistance has been employed for heating the body by which it is inclosed. This method, however, is objectionable, not only because of the great expense involved in the use of the carbon resistance, but also because of the liability to short-circuiting, the inequality in the distribution of heat, and the constant danger of fracture thereof due to concussions to which the body is subjected, especially if of a movable form—such as a sad-iron, foot-rest, or other usual form of device to which electro-heating apparatus is attached—as a result of which the utensil would immediately become useless and would require complete disconnection and the substitution of a new resistance, thereby involving both time and expense.

The object of this invention is to utilize economically the heating effects produced by passing a current of electricity through a conductor of high resistance and low capacity for the purpose of heating stoves, laundry machinery, and sad-irons, and similar utensils, by producing heat in and confining it to such part or parts only of the utensil as is desirable.

Another object is to prevent the heat thus developed from being transmitted either by conduction or radiation to other parts of the same body or to other bodies than those it is desired to heat, and to combine in the maximum degree in an electro-heating apparatus cheapness, durability, compactness, and simplicity of construction.

A further object is to have a metallic resistance, and of such character that it may not only be readily and quickly attached to and detached from the utensil, but may be conformed to any desired configuration of sur-

face to be heated, and so arranged as to operate directly upon and uniformly heat all parts of the surface; and, finally, to dispense with the necessity for chambering or grooving the body of the utensil for reception of the resistance, which has heretofore been found necessary by reason of the peculiar character of the resistance employed, as a result of which the utensil cannot be heated uniformly throughout or near the edges thereof, and to have a resistance of such a character that no chambering is required, and which cannot be fractured when once in its operative position.

These objects are attained by the devices illustrated in the accompanying drawings, in which—

Figure 1 represents a plan view of a cooking-stove embodying my invention; Fig. 2, a similar view showing the top or heating plates of the stove removed, more clearly disclosing the arrangement and disposition of the resistance to these said plates; Fig. 3, an enlarged transverse section on the line 3 3 of Fig. 1. Fig. 4 illustrates the application of my invention to a laundry or other heating roller, and Fig. 5 its application to a sad-iron.

Similar letters of reference indicate the same parts in the several figures of the drawings.

My invention broadly consists in interposing between the surface-plate to be heated and the body supporting the same a reflex metallic resistance, between which and the surface to be heated lies an electric insulator, and between which and the body lies an electric insulating non-conducting heat material for confining the heat to the surface-plate. This general construction is applicable to numerous forms of apparatus and utensils, regardless of their shape or contour, and I have therefore illustrated in the drawings only the more common forms of utensil for which my invention is especially adapted, and which are sufficient to disclose the adaptability thereof to various uses.

Referring now in general terms to the construction common to all of the forms illustrated in the drawings, let A represent the main body, whether stove, roller, or sad-iron,

or any other desirable form of utensil, and B the surface-plate to be heated, secured together by means of screws C, or in any other well-known and convenient manner, between 5 which are interposed, first, a sheet of asbestos cloth or card-board D, or any other suitable electric insulating non-heat-conducting substance lying next to the body of the utensil, to the opposite or outer surface of which is 10 secured the metallic resistance E, consisting of wire of a refractory character reflexed back and forth over the surface of the asbestos sheet, as illustrated in Fig. 2, and preferably secured thereto by any convenient 15 form of fastening—such as sewing with an asbestos thread, staples, and numerous other devices well known in the arts. This metallic resistance is separated from the surface to be heated by another sheet F, of substantially the same size and contour as the sheet D, composed of some electrical insulating substance which is non-combustible and of just sufficient thickness to prevent the wires or other material used as a resistance from 20 coming into contact with the surface-plate to be heated—such, for instance, as very thin asbestos paper, mica, or any other material that fulfills the above requirements—it being understood that this sheet F, while a non- 25 conductor of electricity, should be a fairly good conductor of heat, while the sheet D, on the contrary, should be not only an electric insulator, but a non-conductor of heat, for which reason I prefer that the sheet D should 30 be of thick asbestos and the sheet F of thin mica.

The body A is preferably recessed immediately back of the insulating-sheet D to any desired depth, leaving only thin walls around 40 the sides thereof, which recess is filled with a packing G, of asbestos felt, mineral wool, or some other substance which is a non-conductor of heat, and which, in conjunction with the asbestos sheet D, lying behind the resistance-wires, acts as an insulator for the heat evolved from the resistance, and almost perfectly confines the heat to the surface-plate, preventing it from being wasted in the atmosphere or being conducted to bodies other than 45 those it is desired to heat; and from the construction described it will readily be seen that while the dissipation of heat by radiation is 50 prevented by this layer and packing of asbestos or other non-conducting material its transmission and conduction and dissipation are likewise almost wholly prevented by reason of the only metallic connection between the heated surface-plate and the body of the utensil being the screws or other devices by 55 which they are united together, the asbestos and mica layers interposing therebetween at all points.

The use of a wire of a refractory metal as the heat-generating resistance is preferred, 60 because a large amount of wire can be applied, so as to almost completely cover a surface without any part of the wire coming into

contact with any other adjacent part of the same or other wire, and, being reflexed, prevents self-induction when used with an alternating current; besides which it is well known that the resistance to the passage through metallic wires of electric currents increases with the increase of temperature and decreases with a corresponding decrease of temperature, which principle is of a special benefit in an electro-heating apparatus such as I have described by rendering the utensil self-adapting to the various conditions to which it is subject. A further and equally important advantage in the use of a metallic resistance is its cheapness and the readiness with which it may be shaped to conform to any surface or to any configuration upon a surface which may be desirable. 85

Referring now more particularly to the specific applications of my invention illustrated in the drawings, I will first describe the detailed construction of a stove embodying my invention. (Illustrated in Figs. 1, 2, and 3.) 90 In this as in all other special appliances, the common features exist—namely, the body A, surface-plate B, the resistance E, the electric insulating but non-heat-conducting sheet D, and the electric insulating-sheet F between 95 the resistance and the surface-plate; but in this construction the surface-plate is preferably divided into a series of sections H, the meeting edges of which are beveled, as shown, so as to reduce the area of the metallic contacting surfaces to the minimum, and thus correspondingly reduce the conduction of heat from section to section, and each of which may be heated independently of the other or while the others are in a warm or 100 cold condition; or, if desired, the sections H may be subdivided into smaller sections I, each of which is likewise arranged to be heated independently of the other and having the same general rectangular shape, but of less 105 dimensions than sections H. Still further divisions of the sections may be made by the employment of the circular detached plates J, fitting within corresponding openings in the main plate and sustained therein by 110 radial lugs or projections K, resting upon and corresponding with recesses in the main plate, or in any other convenient manner. 115

Each of the sections H, I, and J has a resistance or resistances connected with the 120 source of electrical energy independently of all of the other sections, one form of disposing of the resistance and their connection with the line-wires L M being illustrated in the diagram view of Fig. 2. For instance, the 125 section H is provided with two independent resistances, but both connected with the same source of supply, the resistance being thus arranged in multiple arc, and, although separate, operate simultaneously to uniformly 130 heat the entire plate. In the plates I the resistances are shown as connected in independent series for each plate, while in the circular plates J two are shown as provided with

independent resistances similar to the plate H, and the other with the resistances in series similar to those of the plates I. The resistance of these sections may be controlled by 5 a switch-board of any desirable form such as is well known in the art to which this invention appertains, for connecting all of the resistances of the section either in series or multiple arc, and for cutting out one or more 10 of the sections while the remainder are in operation; or, if desired, all of the resistances of all of the sections may be thrown into a single series or any other desired combination for producing a desired result, such as 15 the warming of all of the plates or regulating the temperature thereof to any desired degree.

Referring now to the heating-roller illustrated in Fig. 4, the electro-heating apparatus 20 thus is identical in every respect with that of the stove illustrated in Figs. 1, 2, and 3, in so far as relates to the arrangement of the heating surface-plate body and the insulating materials thereof, as well as the dis- 25 position of the resistance-wires between the insulating-sheets, the only difference being in the manner of disposing of the terminals of the resistance and line wires, which in this case must be adapted to make constant 30 contact between a moving and a stationary surface, which, however, may be readily accomplished by having the terminals suitably insulated and connected, respectively, with the insulated metallic rings O P, mounted 35 upon the hub of the roller, against which bear metallic brushes Q R, with which connect the terminals L M of the line-circuit from the source of electrical energy. The general con- 40 tour of this roller, while cylindrical and dif- fering materially from the flat surface of the stove, may be heated in exactly the same manner, the resistance-wires being reflexed over the surface thereof, just as in the case 45 of the stove, and by reason of their flexibility readily conform to the contour of the roller without affecting its function as a resistance in the least degree. So, also, with the flat-iron 50 illustrated in Fig. 5 are the principal elements of my invention disposed and arranged 55 in substantially the same manner as in the constructions previously described, the surface-plate thereof, however, being continuous, as best adapted to the work to be performed, and the resistance being reflexed and ar- 60 ranged in a suitable manner to cover sub- stantially all of the surface-plate, notwithstanding its irregular contour. In this case the terminals of the resistance pass upwardly through the body of the iron to binding-posts 65 S, mounted upon an insulating-block attached to the iron, with which engages a metallic spring-coupling T, of any desired form, to which the terminals of the line-circuit are attached, this coupling serving as a means 70 for readily detaching the iron from the line- 75 wire, and thereby cutting it out of the circuit.

The shell or body of the various devices to which my invention is applied is of just sufficient thickness to withstand mechanical in- 70 jury and still form a rigid structure, the corners, ends, or any intermediate portions thereof being made somewhat thicker than the other portions of the shell to accommodate the screws which fasten to it the removable 75 heating surface-plate.

By the employment of a reflexed wire re- 80 sistance, as described, the heat may be di- rected to and confined at the very edges of the surface-plate to be heated, thus making 85 all portions thereof of a uniform temperature, and when the resistance is fastened to the detachable sheet or card a further advantage is gained by the readiness with which the re- 90 sistance may be changed to suit any voltage of current by simply taking out one card with its wires and substituting another with more or less resistance, as required, which is of especial importance where it becomes nec- 95 essary to change the source of electrical en- ergy, for in all other devices of this class, so far as I am aware, the utensil would have to be changed or reconstructed with very ma- 100 terial change in the electrical pressure.

An apparatus constructed in accordance 95 with my invention combines in the maximum degree cheapness, durability, and simplicity, possessing all of the advantages and none of the disadvantages common to electric heat- 100 ing apparatus as heretofore employed, be- sides having advantages possessed by no other electric heating apparatus, all as fully herein- before set forth.

Having described my invention, what I 105 claim, and desire to secure by Letters Patent, is—

1. In an electro - heating apparatus, the combination, with the body and the heating surface-plate thereof, of an electrical resist- 110 ance lying between said body and plate, a layer of electrical insulating material be- 115 tween said resistance and the plate, and a layer of electrical insulating non-heat-con- ducting material between said resistance and the body, substantially as described.

2. In an electro - heating apparatus, the combination, with the body and the heating surface-plate thereof, of an electrical resist- 120 ance, consisting of a reflexed refractory wire lying between said plate and body, a layer of 125 electrical insulating material between said resis- tance and plate, and a layer of electrical insulating but non-heat-conducting material between said resistance and the body, sub- stantially as described.

3. In an electro - heating apparatus, the combination, with the body recessed on the outer face thereof and the heating surface- 130 plate covering said recess, of a packing of in- combustible non-heat-conducting material filling said recess, an electrical resistance lying between said body and plate, a layer of electrical insulating but non-heat-conducting material interposed between said resistance

and the body, and a layer of electrical insulating material interposed between said resistance and the heating-plate, substantially as described.

5. In an electro - heating apparatus, the combination, with the body and the removable heating surface-plate, of a detachable layer of electrical insulating and non-heat-conducting material between said body and plate, an electrical resistance consisting of a refractory reflexed wire attached to and removable with said layer, and a layer of electrical insulating material between said resistance and the removable heating-plate, substantially as described.

10 6. In an electro - heating apparatus, the combination, with the body and the sectional heating surface-plate thereof, of one or more electrical resistances underlying each section of said plate, a layer of electrical insulating material between said resistances and the plate, and a layer of electrical insulating non-heat-conducting material between said resistances and the body, substantially as described.

CHARLES E. CARPENTER.

W. R. OMOHUNDRO.

the sections of said plate, a layer of electrical insulating material between said resistances and the plate, and a layer of electrical insulating non-heat-conducting material between said resistances and the body, substantially as described.

15 7. In an electro - heating apparatus, the combination, with the body and the sectional heating surface-plate thereof, of one or more electrical resistances underlying each section of said plate, a layer of electrical insulating material between said resistances and the plate, and a layer of electrical insulating non-heat-conducting material between said resistances and the body, substantially as described.
